UNITED STATES PATENT OFFICE.

EDWARD BRUNHOFF, OF CINCINNATI, OHIO.

DESIGN FOR A CHANGE-TRAY.

44,836.

Specification for Design.

Patented Nov. 4, 1913.

Application filed February 10, 1913. Serial No. 747,568. Term of patent 7 years.

To all whom it may concern:

Be it known that I, EDWARD BRUNHOFF, a citizen of the United States, residing at Cincinnati, in the county of Hamilton and State of Ohio, have invented a new, original, and ornamental Design for Change-Trays, of which the following is a specification, reference being had to the accompanying drawings, forming a part thereof.

My new and original design comprises as illustrated a hollow body of transparent material, exteriorly of irregular outline with beveled or sloping sides *a*, a depressed or concave upper face *b* steeply inclined at *b'* and meeting the sides *a* in a comparatively sharp edge *d*, and a bead *f* around the base.

Figure 1 of the drawings is a perspective view and Fig. 2 a central vertical section on line *z z* of Fig. 1.

It is designed to apply colors to the inner face of the body to show through the walls thereof to present a bright and pleasing effect, and the effect of a solid body. Contrasting colors may be applied respectively to faces *a*, *b*, and *f*, and a changeable or fugitive iridescent border may thereby be caused to appear at and close to the edge *d*.

I claim:

The ornamental design for change tray as shown and described.

In testimony whereof, I have affixed my signature in the presence of two witnesses.

EDWARD BRUNHOFF.

Witnesses:

C. W. MILES,
W. THORNTON BOGERT.
